FIG. 2 is a front view of the mesh bag shown in FIG. 1. FIG. 3 is a rear view of the mesh bag shown in FIG. 1. FIG. 4 is a right side view of the mesh bag shown in FIG. 1.

FIG. 5 is a left side view of the mesh bag shown in FIG. 1. FIG. 6 is a top view of the mesh bag shown in FIG. 1. FIG. 7 is a bottom view of the mesh bag shown in FIG. 1. FIG. 8 is an elevated perspective view of a second embodiment of a mesh bag according to a new design.

FIG. 9 is a front view of the mesh bag shown in FIG. 8. FIG. 10 is a rear view of the mesh bag shown in FIG. 8. FIG. 11 is a right side view of the mesh bag shown in FIG. 8.

FIG. 12 is a left side view of the mesh bag shown in FIG. 8.

FIG. 13 is a top view of the mesh bag shown in FIG. 8. FIG. 14 is a bottom view of the mesh bag shown in FIG. 8. FIG. 15 is an elevated perspective view of a third embodiment of a mesh bag according to a new design.

FIG. 16 is a front view of the mesh bag shown in FIG. 15. FIG. 17 is a rear view of the mesh bag shown in FIG. 15. FIG. 18 is a right side view of the mesh bag shown in FIG. 15.

FIG. 19 is a left side view of the mesh bag shown in FIG. 15.

FIG. 20 is a top view of the mesh bag shown in FIG. 15. FIG. 21 is a bottom view of the mesh bag shown in FIG. 15. FIG. 22 is an elevated perspective view of a fourth embodiment of a mesh bag according to a new design.

FIG. 23 is a front view of the mesh bag shown in FIG. 22. FIG. 24 is a rear view of the mesh bag shown in FIG. 22. FIG. 25 is a right side view of the mesh bag shown in FIG. 22.

FIG. 26 is a left side view of the mesh bag shown in FIG. 22.

FIG. 27 is a top view of the mesh bag shown in FIG. 22. FIG. 28 is a bottom view of the mesh bag shown in FIG. 22. FIG. 29 is an elevated perspective view of a fifth embodiment of a mesh bag according to a new design.

FIG. 30 is a front view of the mesh bag shown in FIG. 29. FIG. 31 is a rear view of the mesh bag shown in FIG. 29. FIG. 32 is a right side view of the mesh bag shown in FIG. 29.

(Continued)

FIG. 33 is a left side view of the mesh bag shown in FIG. 29.

FIG. 34 is a top view of the mesh bag shown in FIG. 29.

FIG. 35 is a bottom view of the mesh bag shown in FIG. 29.

FIG. 36 is an elevated perspective view of a sixth embodiment of a mesh bag according to a new design.

FIG. 37 is a front view of the mesh bag shown in FIG. 36.

FIG. 38 is a rear view of the mesh bag shown in FIG. 36.

FIG. 39 is a right side view of the mesh bag shown in FIG. 36.

FIG. 40 is a left side view of the mesh bag shown in FIG. 36.

FIG. 41 is a top view of the mesh bag shown in FIG. 36.

FIG. 42 is a bottom view of the mesh bag shown in FIG. 36.

FIG. 43 is an elevated perspective view of a seventh embodiment of a mesh bag according to a new design.

FIG. 44 is a front view of the mesh bag shown in FIG. 43.

FIG. 45 is a rear view of the mesh bag shown in FIG. 43.

FIG. 46 is a right side view of the mesh bag shown in FIG. 43.

FIG. 47 is a left side view of the mesh bag shown in FIG. 43.

FIG. 48 is a top view of the mesh bag shown in FIG. 43; and, FIG. 49 is a bottom view of the mesh bag shown in FIG. 43. The broken lines represent environmental structure that are for illustrative purposes only and form no part of the claimed design.
